UNITED STATES PATENT OFFICE.

JOHN B. CLERMONT, OF NEW YORK, N. Y.

APPARATUS AND PACKAGE FOR FORMING SOLUTIONS BY PERCOLATION.

1,412,388.

Specification of Letters Patent. Patented Apr. 11, 1922.

Application filed January 11, 1916. Serial No. 71,418.

To all whom it may concern:

Be it known that I, JOHN B. CLERMONT, of New York, in the county of Bronx, and in the State of New York, have invented a 5 certain new and useful Improvement in Apparatus and Packages for Forming Solutions by Percolation, and do hereby declare that the following is a full, clear, and exact description thereof.

10 The object of my invention has been to provide an apparatus for forming solutions by percolation, and a package of material for use in such apparatus, which shall be adapted, among other uses, for use in making coffee, and which shall have any or all 15 of the following advantages:

That of great simplicity; that of enabling infusions to be made of such substances as coffee by passing the water or other liquid 20 but once through the material being leached; that of enabling the material being leached to be introduced into the apparatus and remain therein in the form of a package so as to provide not only for simplicity of 25 operation, but for easily cleansing the apparatus after the operation, and to such ends my invention consists in the hereinafter described apparatus and package for forming solutions by percolation.

30 In the accompanying drawing,

Figs. 1 and 2 are, respectively, a side elevation and a vertical sectional view of a form of apparatus adopted for the practice of my invention;

35 Figs. 3, 4 and 5 are, respectively, a side elevation, a vertical sectional view, and a bottom plan view of a cartridge or package adapted for use with said apparatus.

My invention is capable of use for many 40 different purposes, and while I have chosen for illustrating it the best form of apparatus known to me, such apparatus and package for use therewith, are to be regarded as only one of many possible embodiments, and my 45 invention is not to be restricted thereto.

The illustrated embodiment of my invention is adapted particularly for the manufacture of coffee. In such embodiment, I have shown a base 1 which is adapted to fit 50 over a cup or other vessel into which the made coffee is to drop, such cover having a flange 2 at its outer edge to prevent its escaping from off the cup. In the center of the base is a sleeve 3 which is soldered or 55 otherwise fastened to the base, and which is provided with an inturned flange 4 at its

lower edge. A pot or body 5 is provided with a neck 6 that is adapted to be received within the sleeve, and to rest upon the flange 4, the neck 6 also having an inturned flange 7 at its lower edge. A bayonet joint is formed between the sleeve and the neck by pins 8 on the neck, adapted to engage cam slots 9 in the sleeve. A cover 10 is provided for closing the upper end of the pot. 65

The coffee or other material from which the infusion is to be formed is provided in what I term "cartridges", or packages adapted to be received within the neck of the pot, such packages preferably having 70 substantially vertical walls 11 that are sufficiently impervious to water or other infusing liquid so as to compel all the water escaping from the lower end of the neck to enter perforations 12 formed in the upper 75 part of the cartridge, and thus to insure that the liquid shall all pass through substantially the whole layer of solid material from which the infusion is to be made. I prefer to make the vertical walls of the 80 cartridge of such material as sized paper, but it is obvious that a less waterproof material could be used. The lower end of the cartridge is provided with an outwardly turned flange or shoulder 13, upon which 85 is seated a disc 14 of material which will permit the passage of the water or other liquid while preventing the escape of the solid material, and such disc may be formed of unsized paper like blotting paper. The 90 paper or other material forming the shoulder 13 is preferably turned over underneath the disc 14 to secure it in place. A disc of porous paper may also be used to close the perforations 12 in the cartridge. 95 Both the upper and lower ends of the cartridge may be sealed as by seals 15 and 16 formed, for instance, of paraffine tissue paper, and which are easily torn off.

In the use of my apparatus and cartridge, 100 the cartridge, loaded with pulverized coffee, is made ready for use by tearing off the thin seals 15 and 16, and is placed in the neck 6 of the pot by inserting it in the neck when the pot is inverted, so that the shoulder 105 13 of the cartridge rests on the flange 7 of the neck. The sleeve 3 is then placed over the neck and by means of the bayonet joint is caused to clamp the shoulder 13 and filter disc 14 between the flanges 4 and 7, so as 110 to make a substantially water-tight joint. The pot is then supported upon the cup or

other receptacle which is to receive the coffee extract, and the required amount of water is poured into the pot through its top. The water percolates through the cartridge, and as it can only enter through the perforations 12 and only escape through the porous paper disc, all the water has to pass entirely through the layer of coffee and is all thus equally presented to the pulverized coffee. The result is that the water is in contact with the coffee long enough to take up its beneficial extracts but is not in contact long enough to dissolve its harmful ingredients. In this way, although the water may pass but once through the ground coffee, fluid coffee of the finest flavor may be obtained and with the least amount of deleterious substances therein, and it is found that substantially all of the beneficial materials in the coffee can be extracted with the single passage of the water therethrough.

It will be seen that my apparatus and cartridge have, among others, the following advantages, in addition to those just described:

The use of the cartridge enables the material being leached to be introduced into the apparatus and removed therefrom without ever losing control of the material, so that not only is the operation of charging and emptying the percolator performed with great simplicity and cleanliness, but an infusion is obtained of the greatest possible strength, and all the material being leached is insured of thorough and equal treatment by the water or other liquid. Regulating the size of the cartridge is a convenient and accurate means for measuring the proper amount of coffee or other material to form the desired quantity of the infusion. The apparatus is of great simplicity and can be used out of doors without other facilities than those for supplying hot water.

It is obvious that various changes can be made in the above described embodiment of my invention which would be within the scope of the invention. For instance, the cartridges may be charged with more than a single substance, such, for example, as with

coffee and milk in a dried form, as well as 50 sugar.

I claim:

1. In a percolating apparatus, the combination of a receptacle having a cylindrical neck, a cap having a cylindrical sleeve adapted to fit said neck, said neck and sleeve having inturned flanges on the lower end of said neck and sleeve, means for forcing said flanges toward each other, and a cartridge having a pervious top and bottom, said cartridge having a shoulder adapted to be clamped between said flanges. 55

2. In a percolating apparatus, the combination of a receptacle having a cylindrical neck, a cap having a cylindrical sleeve adapted to fit said neck, said neck and sleeve having inturned flanges on the lower end of said neck and sleeve, a bayonet joint adapted to force said flanges toward each other, and a cartridge having a pervious top and 60 bottom, said cartridge having a shoulder adapted to be clamped between said flanges. 65

3. In combination, a receptacle adapted to contain liquid, a base located beneath said receptacle and having portions shaped to fit 75 over a receiving vessel, said receptacle and base having parts adapted to receive therebetween an independent cartridge containing material to be treated, and a bayonet pin and slot clamping device adapted to draw together said receptacle and base. 80

4. In a percolating apparatus, the combination of a receptacle and a base each having a cylindrical neck or sleeve, said necks or sleeves being provided with opposing flanges or surfaces, a bayonet joint adapted to force said flanges or surfaces toward each other and to clamp the herein-after-mentioned cartridge against one of them, and a cartridge having a pervious top 85 and bottom, said cartridge having a shoulder adapted to be clamped between said flanges. 90

In testimony that I claim the foregoing I have hereunto set my hand.

JOHN B. CLERMONT.

Witness:

EDWIN J. PRINDLE.
